UNITED STATES PATENT OFFICE.

JAMES ROBERT TURNBULL, OF SCRANTON, PENNSYLVANIA.

STEAM-TRAP.

1,334,821.

Specification of Letters Patent. Patented Mar. 23, 1920.

Application filed March 18, 1919. Serial No. 283,329.

To all whom it may concern:

Be it known that I, JAMES R. TURNBULL, a citizen of the United States, residing at Scranton, in the county of Lackawanna and 5 State of Pennsylvania, have invented certain new and useful Improvements in Steam-Traps, of which the following is a specification.

This invention relates to heating systems, 10 and more especially to radiators; and the object of the same is to produce a trap adapted to be attached to a radiator so that the water of condensation therein will be automatically discharged when it reaches a 15 certain volume.

Another object of the invention is to provide means whereby the point of discharge may be regulated from the exterior of the trap.

20 Details of construction are set forth in the following specification and claim, and attention is drawn to the drawings, where-
in—

Figure 1 is a vertical section through 25 this trap complete and Fig. 2 is a horizontal sectional detail on the line 2—2 of Fig. 1.

In the drawings the numeral 1 designates a casing preferably having a removable top 2 with an opening 3 to which may 30 be attached in any suitable manner a vent cock or relief valve and the wall of the casing provided near its top with an inlet opening 4 for the water of condensation. Through the bottom of the casing is an 35 opening in which is screwed an annular nut 5 having a valve seat 6 within the upper end of its bore and a spider 7 in the lower end. Secured to the bottom of the casing is an outlet box 8 having an outlet opening 40 9. By making this box removable and the cover 2 removable, access to the interior of the casing and the parts carried thereby is rendered easy.

Within the casing is disposed a rather 45 heavy float 10 which is hollow and contains air. A pin 11 is screwed as at 12 into the upper end of this float and drives it through a guide 13 at the midlength of the bar 14 carried within the casing, the upper end of 50 this pin by preference being movably mounted within the vent 3. Screwed as at 15 into the lower end of the float is a conical valve 16 adapted to rest upon the seat 6, and at the lower end of the valve is a pin 17 55 which slides within and is guided by the spider 7. In the normal position of this

float as seen in Fig. 1, the valve is closed so that there is no outlet for liquid at the bottom of the casing. When the float rises the pin 11 is guided through the bar 14 at 60 the point 13 and the valve 16 comes off the seat 6 so that there is an outlet for liquid through the annular element 5 and the spider 7 into the box 8. Transversely through the box extends a rock shaft 20 65 mounted in suitable bearings 21 in the side walls of the box and containing within the latter a finger 27 underlying the pin 17. To the outer end of this shaft is secured a lever 22 projecting in a direction opposite to the 70 finger 27 as seen in Fig. 2, and on said lever is mounted a weight 23 which is rendered adjustable by means of a set screw 24. It is essential that this weight shall be less than the weight of the float 10, or in other 75 words the float 10 and the parts carried thereby bearing on the finger 27 must overbalance the weight 23, no matter what the adjusted position thereof.

When now this device is coupled up to a 80 radiator at the inlet point 4, assuming that the radiator is the heating unit of a steam system, water of condensation flows in at 4 and rises within the casing 1 until it eventually lifts the float. Now the water flows 85 through the annular element 5 and past the valve 6 into the box 8 and out at 9. Each time the float rises the casing is relieved of the accumulated water, and it immediately drops back so that the valve 16 is again 90 closed. Should steam flow in at the point 4, it may escape out the vent 3 and it has no effect on the float. The outlet is to a suitable receptacle, or may be coupled up to waste, or in fact might be closed and the overflow 95 water allowed to accumulate within the box 8 and be withdrawn from time to time. This detail is not essential. When the steam of the radiator is maintained at such temperature that there is little or no condensation, it flows in through the inlet 4 and will not raise the float. It is quite possible however, to have the pin 11 substantially close the vent 3 so that there is no appreciable outlet, and I reserve the widest latitude in 100 this respect. Manifestly the adjustment of the weight 23 upon the lever 22 will increase or decrease the lifting tendency of the finger 27 and will therefore advance or retard the moment when the valve 16 will 110 open under the influence of the water rising within the casing 1 around the float 10.

Therefore the operator has means on the exterior of the device for adjusting the point at which it shall act. In addition he can at any time depress the outer end of the lever 22 and cause the forcible rise of the float 10 and discharge of what water has accumulated within the casing; and of course he can at any time disconnect the device to gain access to the interior for purpose of 10 cleansing or repair.

The foregoing description and the drawings have reference to what may be considered the preferred or approved form of my invention. It is to be understood that I 15 may make such changes in construction and arrangement and combination of parts, materials, dimensions, et cetera, as may prove expedient and fall within the scope of the appended claim.

Having thus fully described my invention, what I claim as new and desire to secure by Letters Patent is:—

In a steam trap, the combination with a cylindrical casing having an opening at its bottom, a detachable cover having a vent opening, a bar across the interior of the casing beneath the cover and having a guide 25

beneath said vent opening; an annular element within the opening in the bottom of the casing, and a spider at the lower end of 30 said element having a guide at its center, of a float movably mounted within said casing, a pin at its lower end projecting through the guide in the bar and loosely into said vent, a pin at its lower end projecting through the guide in the spider, and a valve carried by the lower pin and adapted 35 to coact with said valve seat; of a box secured to the bottom of said cylindrical casing and having an outlet, said valve pin 40 depending into said box, a rock shaft extending horizontally through said box and mounted in bearings in the sides thereof, a finger carried by said shaft underlying said pin on the float, a lever carried by the outer 45 end of said shaft and projecting in a direction opposite to that of the finger, and a weight adjustably mounted on said lever.

In testimony whereof I affix my signature in presence of two witnesses.

JAMES ROBERT TURNBULL.
